UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, OF CHICAGO, ILLINOIS, A CORPORATION OF ILLINOIS.

LIGHT-PROJECTING APPARATUS.

Application filed June 28, 1920. Serial No. 392,353.

To all whom it may concern:

Be it known that I, DANIEL J. McCARTHY, a citizen of the United States, residing at Elgin, in the county of Kane and State of

Illinois, have invented certain new and useful Improvements in Light-Projecting Apparatus, of which the following is a specification.

This invention relates to improvements in light projecting apparatus.

One of the objects of the invention is to provide an improved means whereby the full radiant light energy from a source of light may be projected in parallel rays, directly and indirectly, in a given direction.

Another object is to gather the correlated rays of light, radiating in all directions from a single source, and project them in parallel lines in a concentrated intense beam, and when required, subsequently to spread the rays into a larger beam by use of suitably constructed and arranged lenses, thus rendering the field of illumination correspondingly larger and utilizing, in this way, the full light energy of the source of light.

Another object is to provide an improved light reflecting and projecting enclosure within which the lamp is contained and by which a part of the radiant light is reflected back thru the source of light, as a focal point, to a parabolic reflector from which it is projected in parallel rays thru an opening in the enclosure.

The invention broadly considered is a means by which substantially all of the light rays, propagated by a source of light, is projected as from a parabolic reflector.

Some of the rays that do not primarily impinge upon the parabolic reflector, are reflected from radial lines thru the focal point, occupied by the lamp, to the parabolic reflector, and thereby projected with the rays that reach the parabolic reflector directly from the lamp, thus intensifying the beam of projected light and directing practically all of the radiant light energy from the lamp into the beam.

The device may conveniently and economically be used for railway and other signaling apparatus, for railway and automobile head lights and in other situations in which the full effect of a lamp is to be projected in a strong concentrated beam.

Other, further and more specific objects of the invention will become readily appar-

ent to persons skilled in the art, from a consideration of the following description when taken in conjunction with the drawings, wherein:

Fig. 1 shows a sectional view of one form of the apparatus.

Fig. 2 is a similar view of a modified form of the apparatus.

In both views the same reference characters are employed to indicate similar parts.

In both of these views 5 is an enclosure having internally light reflecting surfaces and each enclosure contains a parabolic reflector 6, with a lamp 7 at the focal point of the parabolic reflector. In Fig. 1 the internal reflecting surface 8 is a true ellipse, or elliptic in form. The focal point of the elliptic reflector and of the parabolic reflector coincide at the point at which the concentrated light source is placed corresponding with the lamp 7. 10 is an opening in the reflector 9 thru which the beam of light will pass when projected from the parabolic reflector 6.

The many rays of light emanating from the focal point, or the lamp 7, striking the parabolic reflector 6, will be projected in parallel rays providing a beam of light which will pass thru the opening 10. The plane reflector 9 should be located midway between the two foci of the elliptical reflector 8 and perpendicular to its axis.

A ray of light, such as illustrated by the line 11, coming from the lamp 7 and striking the elliptical surface at 12, will be reflected thereby at such an angle that when it strikes the reflecting surface 9, as at 13, it will be reflected thereby thru the focal point, as by line 14, which focal point is the lamp 7, and thereafter strike the parabolic reflector and then it will be projected from the parabolic reflector, in parallel rays with other similar rays to form a beam of parallel rays which will pass out from the enclosure by way of the opening 10. The rays of light just referred to will be projected from the parabolic reflector in the same manner as if it had been sent direct to the parabolic reflector from the lamp or light source.

By use of the elliptical reflector 8, conjointly with the reflector 9, and in conjunction with the parabolic reflector, the entire radiant energy of the lamp is projected into a beam of parallel rays proceeding from the enclosure, or device, and therefore the total

flux of light from the lamp is concentrated into a beam of the diameter substantially equal to the diameter of the opening 10 and this beam will be many times more intense, 5 or would contain a larger number of light rays, than would be possible to obtain from the projector or parabolic reflector without the co-operation of the reflectors referred to.

In Fig. 2 substantially the same results 10 are obtained, but by the use of two parabolic reflecting surfaces and a curved surface. In this case 6' and 8' are parabolic reflectors whose focal points are both at the source of light. The reflecting surface 9' is a curved 15 surface, so arranged that the parallel rays of light striking it from the parabolic reflector 8' are again reflected back thru the focal point and strike the reflecting surface of the parabolic reflector 6, which sends out, 20 in parallel rays, a beam of light the diameter substantially equal to the opening 10'.

In either case, as illustrated in Figs. 1 and 2, the concentrated beam of light may be spread into a larger beam by the use of 25 a lens combination in which the double curved lens 15, which is a type of lens which tends to spread parallel light rays entering it. The lens 16 is interposed between the lenses 15 and 17 to bend the rays the least 30 possible extent, thus producing a highly efficient lens combination.

The line 18 shows the manner in which the beam is broadened after leaving the container 5 from which it is projected. The 35 line 18 represents a single ray of light which is in parallel relation with other similar rays emanating from the same source, and constituting the beam of projected light.

In each of the structures, illustrated in 40 Figs. 1 and 2, the lamp 7 or 7' is contained within the enclosure providing walls having

internally reflecting surfaces. In many instances the lens 15, 16 and 17 will not be required but in the event that they are desirable, they may be employed for the purpose described. 45

While I have herein shown and described a preferred form, and one modification of the device, it is manifest that other variations will readily be suggested, to persons 50 skilled in the art, which will fall within the scope of the appended claims.

Having described my invention what I claim as new and desire to secure by Letters Patent is: 55

1. A light projecting device comprising an inner reflector substantially parabolic in form and a cooperating outer reflector substantially elliptic 8 in form in which the focal points of the elliptical reflector and of the parabolic reflector coincide to project light in the same direction; a source of light at said focal point and an opposing reflector arranged to return the light proceeding from the elliptical reflector only, thru said focal point to the parabolic reflector. 60

2. A light projecting device comprising a reflector substantially parabolic in form and a cooperating reflector substantially elliptic in form in which the focal points of the elliptical reflector and of the parabolic reflector coincide; a source of light at said focal point and an opposing reflector located in a plane midway between the two foci of the elliptical reflector and perpendicular to the axis of the elliptical reflector, arranged to return the light proceeding from the elliptical reflector, thru said focal point to the parabolic reflector. 75

In testimony whereof I hereunto sub- 80 scribed my name.

DANIEL J. McCARTHY.
